UNITED STATES PATENT OFFICE.

ROY P. M. DAVIS, OF MOUNT UNION, PENNSYLVANIA.

BRICKMAKING MACHINE.

Application filed April 18, 1922. Serial No. 554,561.

To all whom it may concern:

Be it known that ROY P. M. DAVIS, a citizen of the United States of America, residing at Mount Union, in the county of Huntingdon and State of Pennsylvania, has invented certain new and useful Improvements in Brickmaking Machines, of which the following is a specification.

My invention relates to improvements in molds for making bricks.

The object of my invention is to provide an automatic or semiautomatic mold or machine which is capable of making bricks of various sizes and shapes heretofore made by hand.

Another object of my invention is to provide mechanical means for simultaneously moving the sides of the mold toward each other to form the mold, and, or in a reverse direction to release the molded brick.

Still further object is to provide means for swinging the mold and mold frame on a horizontal axis to inverted position to facilitate removal of the brick.

Still another object is to provide means for adjusting the sides and bottom members of the mold to permit of different sizes of bricks being readily made.

Other and further objects and advantages of the invention will be in part explained and in part obvious as the specification is set forth.

In the accompanying drawings forming a part of this specification:

Figure 1 is a perspective view of the invention;

Figure 2 is a top plan view partly in section;

Figure 3 is a bottom plan view;

Figure 4 is a section on line 4—4 of Figure 2.

Figure 5 is an enlarged section through one of the carriages;

Figure 6 is a section on the line 6—6 of Figure 2;

Figure 7 is a section on the line 7—7 of Figure 6;

Figure 8 is a detail section of one corner of the inner frame showing the angle brace;

Figure 9 is a view showing the method of fastening the drive chain to the carriages;

Figure 10 is a bottom view of one of the top plates of the carriages; and

Figure 11 is a detail view of one of the grooved blocks 102.

Referring more particularly to the draw-

ings wherein like reference characters indicate corresponding parts throughout the several views, 1 denotes a rectangular frame preferably formed of heavy boards 2 which constitute the sides of the frame, it being understood that no top or bottom boards are provided. This frame is normally supported by or rests upon a table or other suitable support 3, and it is pivotally connected at one end to a shaft 4 by means of apertured arms 5 secured to and projecting from the lower edge of one of the side boards 2. The shaft 4 is mounted in posts 6 or other suitable supports. The purpose of this pivotal connection is to permit of the frame 1 being swung from its Figure 2 position in which it rests upon the table 3, to an inverted or Figure 3 position to facilitate depositing the completed brick (not shown) upon a vertically adjustable receiving table 7.

The abutting ends of the boards 2 comprising the frame 1 are secured together by means of internal corner fasteners or brackets 8 and external brackets 14, one pair for each corner of the frame. These brackets 8 and 14 also serve as a means for adjustably supporting within the frame 1 a spider 9, the arms 10 of which are apertured to loosely receive the screws 11, in turn mounted for turning movement in the corner brackets. These screws 11 are locked against upward vertical movement in or withdrawal from the brackets 8 and 14 by means of lock nuts 12 which bear against the bottom of the brackets 14. The recessed heads 13 of the screws 11 rest upon and are supported by the top of the brackets 14, it being noted that the outer or external brackets 14 embrace the corners of the frame 1 and overlap the top and bottom of the inner brackets 8.

The arms 10 of the spider 9 are formed with recesses 15 in their under faces to receive the lifting nuts 16 threadedly mounted on the screws 11. These nuts 16 are formed with one straight side as at 17 adapted to abut the end wall of the recesses 15 and in consequence are prevented from making a complete rotation on the screws. Consequently when bolts 11 are turned as by means of a socket wrench (not shown) inserted in the recessed heads 13 of the bolts, the lifting nuts will either ride up or down upon the bolts 11 according to the direction in which the latter are turned. The spider being loosely mounted upon the screws 11,

will be lifted by the nuts 16 as the latter move upwardly on the screws or it will drop by gravity when the nuts 16 are moved downwardly upon the screws 11. Lock nuts 5 17 and lock washers 18 serve to lock the spider in any desired adjusted position.

The function of the spider 9 is to support the bottom mold member or liner plate 69 of the mold, and as will presently be described 10 to adjustably support the spider with relation to the rods or supports 19 and 19' on which the side liners or mold plates 64 and 64' are mounted, and the rods or supports 20 and 20' on which the end liners or mold 15 plates 100 and 100' are mounted.

Located on the outside of the main frame 1 and mounted for vertical movement relatively to frame 1 is a second rectangular frame 23, comprising four side plates 24 20 connected together by the four corner brackets 25. This whole outer frame is suspended from headed bolts 26 mounted in apertured ears 27 radiating from the four corners of the frame 1. The lower ends of 25 the bolts 26 pass through the angle braces 28 with which each corner bracket 25 is provided. Lock nuts 29 on the bolts 26 are screwed against the braces 28 to lock the movable frame against movement relative to the fixed frame after the movable frame has 30 been adjusted, as will be described hereinafter.

The plates 24 of the outer movable frame each have a plate 30 bolted thereto, spacing 35 blocks 81 being employed to space the plates 24 and 30 apart. These plates 30 constitute tracks upon which reciprocating frames or carriages 31 (four in number) travel to and fro as will presently be noted. The carriages 40 31 comprise inner and outer side plates 32 connected together by means of top and bottom rectangular frames 33 and 34 which are respectively bolted to the top and bottom edges of the plates 32. The rectangular 45 frames 33 and 34 overlie the plates 32 and are provided with strips 35 and 36 which engage respectively over and behind the top and bottom edges of the plates 30 thus supporting the carriages for sliding movement.

50 Journalized in suitable bearings in the corner brackets 25 are short shafts 37 fixed to the upper ends of which are sprocket wheels 38 provided with square recesses 39 for the reception of a socket wrench (not shown). 55 A sprocket chain 40 passes around these wheels and is connected at its opposite ends to adjustable screw eyes 41 in turn secured to opposite ends of one of the carriages 31. Adjustment of the screw eyes 41 regulates 60 the tension of the chain. The other three carriages are secured to the chain by means of clamps 42 having out turned ends 43 which ends are adapted to pass through links of the chain and bear against the inner side 65 of plates 44 attached to the lower and inner

portions of the carriages 31. The clamps 42 are adjustably secured to the plates 44 by means of headed bolts 45 the shanks of which pass through narrow longitudinally disposed slots 46 formed in the plates 44. 70 This form of connection permits of the carriages being properly positioned before the bolts 45 are tightened as is most essential in order that the movement of the carriages may be accurately timed. 75

The carriages 31 are supported at their outer edges by clips 47 and 48 secured on the outer ends of spaced aligned bolts 49 and 50 which pass through the carriages and thence through inner and outer plates 51 and 52 covering the large openings or slots 53 formed in the sides of the fixed inner frame 1, it being understood that the bolts 49 and 50 pass through the outer frame 23, thence through the slots 53 thereby clamping the plates 51 and 52 to the frame 1. Lock nuts 54 and 55 and lock nuts 54' and 55' lock the bolts 49 and 50 to the respective frames. To move the outer frames and consequently the carriages 31 vertically with respect to the inner frame 1, it is merely necessary to loosen the lock nuts 54 and 55 whereupon the plates 51 and 52 will be relieved from clamping engagement with the frame 1 and the entire frame 23 may be 90 lifted bodily on the bolts 26. The lock nuts 54 and 55 will then be tightened and the lock nuts 29 on the ends of the bolts 26 will be screwed up against the bottom of the braces 28. As the carriages 31 are fixed to the outer frame 23 against relative vertical movement, vertical adjustment of the one results in a corresponding adjustment of the other with respect to the fixed inner frame 1. Downward adjustment of the frame 23 can of course, be effected in a similar manner to that just described, that is when the lock nuts 54 and 55 and the lock nuts 29 are loosened the outer frame will drop by its own weight to any predetermined lowered position. Such adjustment also affects the rods 19-19' and 20-20', these rods being slidably supported by, and for in and out movement with respect to the carriages 31, as will be presently described. 110

The top frames 33 of the carriages have fixed to the bottom face thereof diagonally disposed bars 56-56' and 57-57' formed at one extremity with offset portions 58-58' and 59-59' extending parallel with the frames 1 and 23. These rods 56-56' and 57-57' slidably engage in slots 60 and 61 formed in the upper face of the blocks 102 in turn secured to the push rods 19-19' and 20-20' by means of set screws 91. It will be noted that the slots 60 are transversely disposed and that the slots 61 are angularly disposed with respect to and bisect the slots 60. The offset portions of the bars 56-56' 120 125 130

extend in the same plane as that of the transverse slots 60 and the diagonally disposed portion of these bars 56—56' extend in the same plane as that of the angularly disposed slots 61. Consequently when the carriages 31 are moved from one corner to the other of the outer frame 23 the bars 56—56' and 57—57' will engage first in one of the slots 60 and 61 and then in the other 10 and the push rods will be forced towards the interior center of the frame 1 or withdrawn therefrom as the case may be according to the direction of travel of the carriages 31. It may here be noted that the 15 push rods 19—19' and 20—20' extend through the carriages 31, through the frame 23 and thence through the plates 51 and 52 (and of course through the large opening or slot 53) into the interior of the frame 1. 20 This movement of the carriages is effected by turning the shafts 37 by means of a socket wrench (not shown) or any other suitable means.

The push rods 19—19' are provided with 25 heads 62—62' to which are bolted what may be termed side liner plate supports 63—63', to which in turn are bolted the side liner or mold plates 64—64' and the push rods 20—20' have heads 65—65' to which are 30 bolted end liner plate supports 67—67' to which are secured the end liner on mold plates 100—100'. Secured to the top face of the spider 9 is a plate 68 to which is bolted the bottom liner plate 69, such liner 35 plates when in Figure 2 position constituting the mold in which the brick is made. It will be understood that the liner plates may be of various configurations, such as the tongue and groove construction shown 40 according to the particular type or shape of brick which it is desired to make.

By reason of the fact that the side liner plates are of greater length than the end liner plates and the former have a greater 45 distance to travel than the latter, some means must be provided for causing the push rods 19—19' to move outwardly toward Figure 4 position, slightly in advance of the corresponding movement on the part 50 of the push rods 20—20', or at greater speed.

It is desirable if not absolutely essential that the limit of inward movement of both pairs of push rods be reached simultaneously, consequently if the initial outward 55 movement of the push rods 20—20' is delayed beyond that of the initial outward movement of the push rods 19—19' and the latter have a greater distance to travel it follows that in order to accomplish the de- 60 sideratum previously mentioned the movement of the push rods 19—19' must exceed in speed the corresponding movement of the push rods 20—20'. This delayed outward movement of the rods 20—20' is effected by 65 my making the offset portions of the bars

57—57' shorter than the corresponding portions of the bars 56—56' whereby the carriages 31 will have a slight movement before the angular portion of the bars 56—56' engage the blocks 102. The acceleration in 70 speed during both inward and outward movement of the push rods 19—19' is obtained by making the bars 57—57' shorter and of great angularity than the bars 56—56' thus increasing the throw of the former bars. 75

When the blocks 102 are in Figure 2 position, it will be noted that they engage behind the blocks 70 bolted to the under faces of the top frames 33 of the carriages 31 thereby relieving the bars 56—56' and 80 57—57' of strain.

From the foregoing it is believed that the operation of my invention will be readily understood but the same may be briefly described as follows:

Assuming that the side and end liner plates 64—64' and 67—67' have been secured to the push rods 19—19' and 20—20' respectively and have been set to make the proper sized brick, the blocks 62 are locked to the push rods by the set screws 91. The bottom liner plate 69 of the molds is then bolted in proper position on the plate 68 carried by the spider 9 and the spider raised to the desired vertical position by manual actuation of the headed control screws 11, it being understood that any suitable power control means (not shown) for actuating the screws 11 either individually or in unison may be employed for this purpose. After 100 the spider has been locked the mold is ready for the operation of making brick.

A charge of "mud" is now deposited by gravity into the open top of the mold in any suitable and well known manner (not shown). After the mold has been filled the top of the brick is smoothed off by means of a rotary slicker (not shown) and a pallet (not shown) is clamped over the top of the mold by suitable fasteners (also not shown). The entire inner and outer frames 1 and 23 are then swung to inverted or Figure 3 position on the shaft 4 as a pivot, until the said frames rest upon the vertically movable table 7.

The operator now rotates one of the short shafts 37 in the appropriate direction which causes the carriages 31 to move in unison across the sides of the frame 23, thereby withdrawing the push rods and the liner plates carried thereby outwardly towards the sides of the frame 1. The side and end liner plates are thus completely withdrawn from contact with the brick and consequently no matter what the configuration of brick may be, when the fasteners of the pallet are unlocked from the frame 1, the brick will be deposited uninjured together with the pallet upon the table 7. The latter is then lowered and the brick removed. It 130

will be understood that any suitable power means (not shown) may be employed for rotating the shafts 37.

After the brick has been removed the frames 1 and 23 are swung back to Figure 1 position and the operation repeated.

Having thus described my invention, What I claim is:

1. A mold for making brick comprising a frame, means in said frame for supporting the bottom liner plate of the mold, means for vertically adjusting said aforementioned means, means for supporting the side and end liner plates of the mold, and means for causing said side and end liner plates to move inwardly towards or outwardly away from each other, and said frame being movable to inverted position.

2. A mold for making brick comprising a frame, a vertically adjustable support in the frame for the bottom liner plate of the mold, slideable members extending through the sides of said frame, said members adapted to carry the side and end liner plates of the mold, supports on the outside of said frame, carriages on said supports for actuating said slideable members, and means for actuating said carriages.

3. A mold for making brick comprising a frame, a vertically adjustable support in said frame for the bottom liner plate of the mold, supports for the side and end liner plates of the mold extending radially through said frame, means for adjusting said last mentioned supports in a vertical direction with respect to said frame, and means for adjusting said supports in a radial direction.

4. A mold for making brick comprising a frame, a vertically adjustable support in said frame for the bottom liner plate of the mold, supports for the side and end liner plates of the mold extending radially through said frame, means for adjusting said last mentioned supports in a vertical direction with respect to said frame, means for adjusting said supports in a radial direction, and said frame being movable to an inverted position.

5. A mold for making brick comprising

an inner frame, a support in said inner frame for the bottom liner plate of the mold, means for adjusting said support in a vertical direction, an outer frame supported by and vertically adjustable with respect to said inner frame, rods supported by said outer frame, and extending inwardly through said inner frame, said rods having means on their inner ends for carrying the side and end liner plates of the mold, carriages movable on said outer frame for actuating said rods, and means for actuating said carriages.

6. A mold for making brick comprising a frame, a support in said frame for the bottom liner plate of the mold, rods slideable through the sides of said frame, means on the ends of said rods for carrying the side and end liner plates of the mold, grooved blocks secured to said rods, carriages mounted on said frame for sliding movement, angularly disposed bars on said carriages engaging in said plates to cause said rods to move inwardly when said carriages are moved in one direction and causing said rods to move outwardly when said carriages are moved in an opposite direction, and means for causing said carriages to move simultaneously.

7. A mold for making brick comprising a frame, a support in said frame for the bottom liner plate of the mold, rods extending slidably through the sides of said frame, means on the inner ends of said rods for carrying the side and end liner plates of the mold, and means for actuating certain of said slideable rods at greater speed than others of said rods.

8. A mold for making brick comprising a frame, means in said frame for supporting the bottom liner plate of the mold, means for vertically adjusting said aforementioned means, means for supporting the side and end liner plates of the mold, means for causing said side and end liner plates to move inwardly towards or outwardly away from each other, and means for controlling the distance and direction of movement of said side end and bottom liner plates.

In testimony whereof I affix my signature.

ROY P. M. DAVIS.
